ATTORNEY

UNITED STATES PATENT OFFICE

BERTHA SEELIG, OF KANSAS CITY, MISSOURI

TOOTHBRAHSH

Application filed August 24, 1928. Serial No. 301,809.

My invention relates to tooth brushes and more particularly to devices of that character in which a brush is operated in one direction by a plunger which tensions a spring for operating the brush in the other direction, the principal objects of the invention being to adjust the length of the path over which the plunger reciprocates and to vary the speed of the return stroke.

10 Further objects are to enclose a plunger returning spring in an imperforate portion of the brush support, to latch the spring adjustably to the support, and to facilitate the mounting of the spring in the support. Another object is to provide a compact device having relatively few parts which may be easily and quickly assembled and readily adjusted and in which the parts are protected from intrusion of moisture and other deleterious substances.

In accomplishing these and other objects of the invention, I have provided improved details of structure, the preferred forms of which are illustrated in the accompanying drawings, wherein:

Fig. 1 is a detail perspective view of the device illustrated as supported by a hand for operating the same.

Fig. 2 is a central longitudinal sectional view of the device.

Fig. 3 is a detail perspective view of the brush and brush-supporting mandrel.

Fig. 4 is a transverse sectional view on the line 4—4, Fig. 2, illustrating the rack and pinion means for operating the brush.

Fig. 5 is a detail perspective view of the cap for latching the plunger-returning spring to the barrel.

Fig. 6 is a detail perspective view of the opposite ends of the plunger returning spring.

Referring in detail to the drawings:

1 designates a barrel having a reduced upper end 2 and an internal annular bearing boss 3, and 4 designates a shaft journaled in the reduced end 2 and boss 3 and having an axially bored split portion 5 extending beyond the barrel to receive a mandrel 6 having a collar 7 in which the bristles 8 are mounted, the mandrel having a flat

trunnion 9 on its lower end receivable in a socket 10 of the shaft for latching the mandrel in the shaft against rotation.

Rack and pinion means for actuating the shaft are illustrated as preferably comprising a pinion 11 fixed to the shaft and a rack bar 12 slidable in a guide 13 formed on the barrel and extending transversely thereof, whereby the rack bar may move reciprocably in engagement with the pinion for rotating the shaft to operate the brush. The barrel is cut away as at 14 to admit the rack into engagement with the pinion, and shoulders 15 are formed on the barrel to cooperate with the guide member 13 in supporting the rack.

The rack is adapted to operate the brush rotatably in one direction, and a spring 16 is provided for returning the rack to pre-operating position, the spring preferably comprising a wire formed into a coil and having a radially inturned upper end comprising a latching finger 17 movable into and through a slot 18 extending longitudinally in the shaft from the lower end thereof to a point 19 adjacent the ratchet, whereby the spring may be mounted on the shaft and moved therewith for complete enclosure by the barrel. A pin is fixed in the outer end of the rack to stop the same and prevent the rack from escaping from the barrel when actuated by the spring.

Mounted on the lower end of the barrel to retain the spring and shaft is a cap 20 comprising a body 21 and a reduced sleeve 22 slidable in the lower end of the barrel, the sleeve being provided with a longitudinal slot 23 to receive a longitudinally outbent latching end or finger 24 of the wire forming the spring. The sleeve is slidable longitudinally into the barrel over the lower end of the shaft into engagement with the spring, and when so mounted is frictionally latched to the barrel to anchor the spring, but may be rotated to vary the tension of the spring.

The body member has an axial recess 25 to receive the lower end of the shaft which comprises a journal opening for supporting the shaft, and a transverse opening 26 to

receive means such as a rod adapted to overcome the frictional resistance of the barrel-engaged sleeve for rotating the cap to vary the tension of the spring. The shoulder 27 formed by the reduction of the cap member to provide the sleeve, seats against the lower end of the barrel when the cap is in shaft-engaging position.

The parts being constructed as described, 10 the shaft may be inserted in the barrel through the lower open end thereof, the pinion engaging the boss and stopping the shaft in position for engagement of the rack bar with the pinion.

15 The coil spring is then inserted in the barrel, the indent finger moving in the shaft slot, and the cap is applied, the sleeve sliding into the lower end of the barrel and fitting tightly therein. The lower finger of 20 the spring member extends in spaced relation with the axis of the spring, and is slidably received in the slot of the sleeve, and the axial recess of the cap body receives and journals the lower end of the shaft. The 25 cap therefore frictionally latches the spring to the barrel. When the barrel is held in the hand of an operator, movement of the rack bar in one direction to rotate the shaft will tension the spring, and when the rack 30 is released the spring will unwind and move the shaft rotatively in the other direction, for rotating the brush and restoring the rack to preoperating position.

A suitable tool may be inserted in the 35 transverse opening of the cap, for turning the cap to relieve or increase the tension of the spring.

It is apparent that when the parts are 40 originally assembled, the rack bar being in completely retracted position, there will be no tension on the spring. When the brush is used, the entire rack bar will move over the pinion, so that a relatively large predetermined number of rotations of the shaft 45 will occur and the spring will be tensioned sufficiently to return the bar to completely retracted position, the shaft being actuated by the spring at relatively low speed.

The cap may be turned anti-clockwise in 50 the illustrated structure to set up initial tension of the spring whereby the rack bar will be held yieldingly in extreme retracted position, more force will be necessary to move the bar, and the spring will move the shaft and bar retractively at higher speed.

The cap may be turned in the opposite or 55 clockwise direction, for relieving the pressure on the rack bar, and may be turned sufficiently to rotate the shaft so that the ratchet moves the rack bar away from completely 60 retracted position, and the bar will be at rest in the position shown in Fig. 1, whereby the driving stroke of the plunger or rack bar is reduced, and the spring will return the 65 bar to its initial position.

What I claim and desire to secure by Letters Patent is:

1. A rotary tooth brush support comprising a barrel, a shaft within the barrel having a longitudinal slot, a coil spring surrounding the shaft having a finger slidable in the slot for latching the spring to the shaft, means for latching the opposite end of the spring to the barrel, and means including a rack and pinion for rotating the shaft in one direction to tension the spring for rotating the shaft in the opposite direction. 70

75 2. A device of the character described including a support comprising a barrel, and a shaft rotatably supported by the barrel, rack and pinion means for rotating the shaft in one direction, a spring engaged with the shaft and adapted to be tensioned by said one-way rotation of the shaft for rotating the shaft in the opposite direction, a longitudinally out-turned finger on the spring, and spring-anchoring means on the barrel having slidable engagement with said finger, said means being movable for adjusting the tension of the spring. 80

85 3. A device of the character described including a support, a brush-supporting slotted shaft journaled in the support, means for rotating the shaft in one direction, and means for rotating the shaft in the other direction, including a spring having a radially inturned finger slidable longitudinally in the slot of the shaft and a longitudinally out-turned finger engageable with the support. 95

100 4. A rotary tooth brush comprising a barrel, a shaft having a longitudinal slot, a coil spring having a finger on one end adapted to move in the slot for mounting the spring on the shaft to latch the spring to the shaft, means including a cap frictionally engaged with the barrel for adjustably latching the opposite end of the spring to the barrel, and means for rotating the shaft in one direction to tension the spring for rotating the shaft in the opposite direction. 105

110 5. A rotary tooth brush comprising a barrel, a brush-supporting shaft journaled in the barrel, means for rotating the shaft in one direction, and means for rotating the shaft in the other direction including a spring having a radially inturned finger engageable with the shaft, a longitudinally out-turned finger on its opposite end, and a cap having a sleeve slidable in the barrel having a slot to receive said out-turned finger of the spring for slidably mounting the cap in the barrel in slidable engagement with the spring. 115

120 6. In a device of the character described, a barrel, a shaft rotatable in the barrel, means for rotating the shaft in one direction, means for rotating the shaft in the other direction including a coil spring, 125

means for engaging one end of the spring with the shaft, and means for anchoring the opposite end of the spring to the barrel including a cap frictionally engageable with the barrel and provided with an axial recess 5 to receive the outer end of the shaft for centering the shaft and having a slot offset laterally from the recess to receive said opposite end of the spring for removably engaging the cap with the spring.

10 In testimony whereof I affix my signature.
BERTHA SEELIG.
